UNITED STATES PATENT OFFICE.

ARTHUR E. PETERS AND MORTIMER S. PARKHILL, OF LITTLETON, COLORADO, AS
SIGNORS TO INGERSOLL-RAND COMPANY, OF JERSEY CITY, NEW JERSEY, A COR-
PORATION OF NEW JERSEY.

SHARPENER FOR DRILL STEELS.

Application filed December 14, 1923. Serial No. 680,688.

To all whom it may concern:

Be it known that we, ARTHUR E. PETERS and MORTIMER S. PARKHILL, citizens of the United States, and residents of Littleton, 5 county of Arapahoe, and State of Colorado, have invented a certain Sharpener for Drill Steels, of which the following is a specification, accompanied by drawings.

This invention relates to drill sharpening 10 and forging machines, but more particularly to the pneumatically operated machines for sharpening drill steels.

The type of drill sharpening device to which this invention is more particularly 15 applicable, is that in which there is provided a clamping head operated by a large piston on its downward stroke and a small piston for raising or separating the clamping elements. The raising cylinder in which the 20 smaller piston reciprocates, is operated with motive fluid only at such times when it is desired to raise the clamping member, at other times the fluid is exhausted slowly through a suitable valve to form a cushion.

25 The object of the cushion is to prevent the clamping jaws from striking together under the full force of motive fluid and in this manner to eliminate the tremendous shocks which might weaken the machine.

30 The object of this invention is to enable the cushion to be formed in the smaller cylinder and to be controlled by the main valve, which controls the other operating parts of the machine. In the particular embodiment hereinafter described, the bleed or 35 release of motive fluid from the raising cylinder is permitted through the controlling valve proper, thereby eliminating unnecessary apparatus and providing a simple construction.

40 Another object of the invention is to provide a free exhaust for the motive fluid from the various operative portions of the machine.

45 Other objects of the invention will become apparent from the following description taken in conjunction with the drawings, in which there is illustrated a practical embodiment, and in which—

50 Figure 1 is a side elevation of a pneumatic drill sharpening machine, partly in section disclosing the interior of the controlling valve and the driving portions of the machine.

Figure 2 is a vertical section of the controlling valve in the valve chest showing the valve in its first operating position. 55

Figure 4 is a vertical section of the valve and valve chest showing the third operating position, and 60

Figure 5 is a section taken through the valve and valve chest showing the exhaust passages and connections for moving the valve. 65

Referring to the drawings, and more particularly to Figure 1, the machine is provided with a base A upon which is mounted a main cylinder B to accommodate a large piston C which terminates at its lower end in a smaller piston D, the base A being bored accurately to receive the smaller piston, and being closed by base plug A'. The upper portion of the cylinder B forms an anvil block E upon which the drill steels are forged and clamped as is usual in machines of this type. A clamping head F is adapted to be raised and lowered upon reciprocation of the piston C and is attached to that piston by means of the cross head rods G extending through the anvil block E and bolted to the piston C by means of the nuts H. The arrangement of the apparatus is such that when motive fluid, such as for instance compressed air, is admitted above the large piston C, the cross head F is lowered with great force to act as a hammer against the drill steel placed on the anvil block E, and if desired the pressure may be maintained in the cylinder B which is hereinafter termed the clamping cylinder, in order to grip the steel as in a vise. The raising of the cross head F is accomplished by exhausting the air from the clamping cylinder B and admitting compressed air to the raising cylinder J below the smaller piston D. Dolly operations are performed upon a drill steel clamped between the cross head F and the anvil block E by means of dolly apparatus of any suitable type having a dolly cylinder as indicated at K. 95

100 Suitable air connections are provided to the raising cylinder J, the clamping cylinder B and the dolly cylinder K, the distribution of air for actuating the various devices being controlled by a valve L preferably of the spool type, which is manually controlled through connecting lever and link O and P by a lever Q mounted on the exterior of the

valve chest R. The ports and passages in the valve chest, which are controlled by the valve L, are shown in Figures 2, 3, 4 and 5. The motive fluid is supplied to the valve chest through a port S from a suitable source. The raising cylinder is supplied with air through a pipe connection T, which is associated in the valve chest with a port U similar to the pipe connection V, which 10 conducts air to the dolly cylinder K from a port W in the valve chest. Motive fluid is admitted to the clamping cylinder B through a port X in the valve chest, which connects with the cylinder B through a passage Y in the wall of the cylinder. The exhaust from the various cylinders is conducted through individual paths, that of the clamping cylinder passes through a port Z to atmosphere, while the exhaust from the 15 dolly cylinder is led out through the structure of the dolly cylinder itself as is usual in devices of this character. In order to form a cushion within the raising cylinder J below the smaller piston D, the exhaust 20 from the cylinder is restricted and escapes through small perforations a, b, and c in the lower enlarged portion of the valve L.

The arrangement of the ports U, S, X, W and Z is such that the valve has three consecutive operating positions. In its first position, as shown in Figure 2, and in which the valve L is moved to its lower operating position, the port U communicates with the supply port S through the bore of the chest 30 so that motive fluid flows directly into the raising cylinder J. At this position of the valve L, the clamping cylinder B is in direct communication with a chamber d which leads to atmosphere both around the inner shell e of the valve chest through a passage-way f, or through the hollow bore of the valve. The passage-way f is provided to give sufficient freedom of exhaust to the large 35 quantity of air to be exhausted from the clamping cylinder. Also in this first position, the port X is blanked by the valve L, so that there is no supply of air to the clamping cylinder and in addition, the port W associated with the dolly cylinder is 40 closed.

Upon raising the valve L to its second operating position as shown in Figure 3, the supply of motive fluid to the port W is cut off from the port S by the larger diameter portion of the valve, and the port X is associated with the supply port S admitting air to the clamping cylinder B to depress the piston C whereupon the cross head F is lowered to its clamping or forging position. Simultaneously the exhaust port Z is closed, preventing the escape of motive fluid from the clamping cylinder and the dolly cylinder is cut off from the supply of motive fluid by the closure of the port W. In this 65 position, the motive fluid in the raising

cylinder J is bled to atmosphere through the first perforation a in the valve L. Under these conditions, the cross head F is lowered, forcing out the motive fluid from the raising cylinder J and the dolly cylinder is inactive there being no motive fluid being supplied thereto.

In the third position of the valve, as shown in Figure 4 wherein the valve L is raised to its uppermost extent, the motive fluid is still being exhausted from the raising cylinder through the perforations c and the valve is in such position that the supply port S for the motive fluid is in communication with the port X to maintain the full pressure in the clamping cylinder B, the exhaust port Z of the clamping cylinder being still closed by the valve. In its upward travel, the valve L uncovers the port W leading to the dolly cylinder and the pressure motive fluid is permitted to pass from the supply port S through the bore of the valve chest, through the port W to the dolly cylinder.

The valve thus has three consecutive operating positions, the first shown in Figure 2, in which the raising cylinder is supplied with motive fluid to raise the cross head F, which permits the removal or insertion of the drill steel between the cross head F and the anvil block E. The second position, shown in Figure 3 is for clamping or forging the drill steels between the anvil block E and the cross head F. In forging a drill 100 steel the first two positions only may be used to shape the sides of the drill steel shank. The third position shown in Figure 4 is useful to operate the dolly cylinder for sharpening or dollying the end of the drill previously clamped between the anvil block 105 E and the cross head F.

Suitable plugs indicated at g and h provide access to the interior of the valve chest R and if desired, the chamber j which is closed by the plug h, may be used as a reservoir for lubricant or a lubricating device, as for instance of the cartridge type. The lower part of the valve chest through which the exhaust escapes to atmosphere may be provided with a plate k bolted or otherwise 110 suitably attached to cover the opening and may have a threaded aperture o therein by which a pipe coupling may be connected to lead off the exhaust.

We claim:

1. In a drill sharpening device, a clamping cylinder, a raising cylinder and a dolly cylinder, a valve having three consecutive operating positions and adapted to connect a supply of motive fluid with said raising cylinder in the first position and to exhaust the clamping cylinder to atmosphere; to associate said motive fluid supply with said clamping cylinder in the second position and to bleed said raising cylinder; and in 125

- the third position to associate said clamping cylinder and said dolly cylinder with said motive fluid supply and to continue to bleed said raising cylinder.
- 5 2. In a drill sharpening device, a clamping cylinder, a raising cylinder and a dolly cylinder, a valve having three consecutive operating positions and adapted to connect a supply of motive fluid with said raising cylinder in the first position and to exhaust the clamping cylinder to atmosphere; to associate said motive fluid supply with said clamping cylinder in the second position and to bleed said raising cylinder; and in the 10 third position to associate said clamping cylinder and said dolly cylinder with said motive fluid supply and to continue to bleed said raising cylinder, said valve being hollow to conduct the exhaust therethrough to 15 atmosphere.
- 20 3. In a drill sharpening device, a clamping cylinder, a raising cylinder and a dolly cylinder, a valve having three consecutive operating positions and adapted to connect a supply of motive fluid with said raising cylinder in the first position; and to exhaust the clamping cylinder to atmosphere; to associate said motive fluid supply with said clamping cylinder in the second position, 25 and to bleed said raising cylinder; and in the third position to associate said clamping cylinder and said dolly cylinder with said motive fluid supply and to continue to bleed said raising cylinder; said valve being hollow to conduct the exhaust fluid therethrough to 30 atmosphere, and provided with an aperture therethrough communicating with the raising cylinder and the interior of the valve.
- 35 4. In a drill sharpening device, a clamping cylinder, a raising cylinder and a dolly cylinder, a valve having three consecutive operating positions and adapted to connect a supply of motive fluid with said raising cylinder in the first position and to exhaust the clamping cylinder to atmosphere; to associate said motive fluid supply with said clamping cylinder in the second position, and to bleed said raising cylinder; and in the 40 third position to associate said clamping cylinder and said dolly cylinder with said motive fluid supply to continue to bleed said raising cylinder, said valve being hollow to conduct the exhaust fluid therethrough to atmosphere, and provided with a plurality of apertures through the valve to maintain a fixed degree of bleeding of the raising cylinder to atmosphere in the second and third 45 positions of the valve.
- 50 5. In a pneumatic drill sharpening device, a raising cylinder, a clamping cylinder and a dolly cylinder, a valve chest, a valve recip- 55

- rotatory in said valve chest and having three operating positions in the first of which motive fluid is supplied to said raising cylinder, and the clamping cylinder is exhausted to atmosphere; motive fluid being supplied to the clamping cylinder in the second position of the valve, and the raising cylinder being exhausted gradually to atmosphere, and in the third position the motive fluid being supplied to the clamping cylinder and the dolly cylinder while the raising cylinder is gradually exhausted to atmosphere, said valve chest being provided with passages leading from both ends to atmosphere and said valve being hollow to conduct exhaust fluid therethrough.
6. In a pneumatic drill sharpening device, a raising cylinder, a clamping cylinder and a dolly cylinder, a valve chest, a valve reciprocatory in said valve chest and having three operating positions, in the first of which motive fluid is supplied to said raising cylinder, and the clamping cylinder is exhausted to atmosphere; motive fluid being supplied to the clamping cylinder in the second position of the valve, and the raising cylinder being exhausted gradually to atmosphere; and in the third position the motive fluid being supplied to the clamping cylinder and the dolly cylinder while the raising cylinder is gradually exhausted to atmosphere, said valve chest being provided with passages leading from both ends to atmosphere and said valve being hollow to conduct exhaust fluid therethrough and provided with a plurality of apertures extending to the interior of the valve for gradually exhausting the motive fluid from the raising cylinder in the second and third positions of the said valve.
7. In a drill sharpening device a clamping cylinder, a raising cylinder and a dolly cylinder, a valve having three consecutive operating positions and adapted to connect a supply of motive fluid to said raising cylinder in the first position and to exhaust said clamping cylinder to atmosphere; to associate said motive fluid supply with said clamping cylinder in second position and to bleed said raising cylinder; and in the third position to associate said clamping cylinder and said dolly cylinder with said motive fluid cylinder but continue to bleed said raising cylinder, said valve being provided with means to maintain a fixed degree of bleeding of the raising cylinder to atmosphere in the second and third positions of the valve.
- In testimony whereof we have signed this specification.
